LOCK KNIFE FOR LOOMS

Application filed January 23, 1931. Serial No. 510,741.

This invention relates to improvements in lock knives for so-called vibrators of Knowles looms and it is the general object of the invention to provide a construction which shall be rendered more dependable by transmitting the force from the actuating cam to the lock knife by improved connections.

In the so-called Knowles loom there are employed a series of vibrator levers which are raised or lowered as the case may be to present vibrator gears to one or another of a pair of oppositely rotating mutilated cylinder gears. The vibrator gears which mesh with the lower cylinder have a tendency to rise which is checked by a lock knife so controlled as to prevent vertical movement of the vibrator lever during the time that the vibrator gear meshes with the cylinders. As heretofore constructed these knives have been actuated by a cam acting through a series of connections including a rocking shaft which is rotated by a force transmitted through set screws. The latter transmit the rotative movement of a lever to a shaft and because of this arrangement there is a likelihood that the screws will work loose and thus destroy the proper timing of the knife with resultant breakage. It is an important object of my present invention to so arrange the connections between the cam and the lock knife that reliance for the transmission of operating force need not depend on screws transmitting a torsional strain. To this end I provide co-operating parts which act to place the engaging parts of the connection in compression, this type of strain having no tendency to destroy the proper setting of the parts in a rotative direction.

It is another object of my invention to provide a pair of directly engaging members one of which is a lock knife frame and the other of which is an actuating lever having engagement with an operating cam.

With these and other objects in view which will appear as the description proceeds, my invention resides in the combination and arrangement of parts hereinafter described and set forth in the claims.

In the accompanying drawing wherein a

convenient embodiment of my invention is set forth,

Fig. 1 is a front elevation of a portion of a Knowles head having my invention applied thereto,

Fig. 2 is a detailed vertical section on line 2—2 of Fig. 1 showing the lock knife frame and associated parts, and

Fig. 3 is a diagrammatic view of the operating cam.

In the accompanying drawing the loom frame 10 supports top and bottom cylinders 11 and 12, respectively, which are in effect elongated mutilated gears which coact with vibrator gears 13. The latter are mounted on vibrator levers 14 which are pivoted around a heel pin 15 and are positioned by a pattern mechanism designated generally at 16. The latter moves in timed relation with the loom and acts to give the several vibrator levers a different setting for each flight of the shuttle. Each vibrator lever has rotatably mounted thereon one of the vibrator gears and each of the latter has a connector 17 which is attached to the corresponding harness jack 18.

By means not shown the mutilated cylinder 11 and 12 are caused to rotate in opposite directions, the upper cylinder coacting with the vibrator gears of the levers which are raised and the lower cylinder similarly coacting with the gears 13 corresponding to the vibrator levers in lower position.

A guide comb 19 is fixed to the loom frame and serves to space the vibrator levers as suggested in Fig. 2.

Each vibrator lever is provided with a locking tip 20 projecting to the right of the comb as shown in Fig. 1. The latter coacts with a lock knife or blade 21 which is mounted on the horizontal supporting table 23 forming part of the lock knife frame designated generally at 22 and having supporting arms 25 which in the present instance may rotate freely about a fixed shaft 26. The latter may be journaled in the loom frame.

The upper cylinder 11 is provided with a shaft 27 which projects forwardly from the cylinder and has keyed thereto an operating cam 28 which cooperates with an actuating lever 29 carrying a roll 30. As shown in

Fig. 3 the latter has a low dwell 31 which need not necessarily be in engagement with the roll, and having a high dwell 32 which engages the roll at such times as the lock 5 knife is to be moved out of locking engagement with respect to the vibrator levers. The lever 29 is pivoted as at 33 to the loom frame and has a depending arm 34 which carries a stop screw 35. The latter is positioned 10 for engagement with the comb or any other fixed part of the loom and may be so adjusted as to keep the roll just clear of the low dwell 31. Said depending arm 34 is provided with a second screw or similar abutting 15 element 36 which has engagement with a portion of the lock knife frame 22.

A relatively heavy tension spring 37 is interposed between a fixed stop 38 and a finger 39 forming part of the lock knife frame 22. 20 The effect of the spring is to hold the frame against the screw 36 and cause the latter to move the arm 34 to the left as viewed in Fig. 1 until the stop screw 35 engages the comb 19. In this way a single spring tends 25 to move the lock knife blade toward the tips 20 and also positions the lever 29.

In operation the cylinders 11 and 12 will rotate and the cam 28 will depress lever 29 so as to cause rocking movement thereof 30 around the pivot 33 in a counter clockwise direction as viewed in Fig. 1. The effect of this movement is to cause the screw 36 or other similar abutting element carried by the arm 34 to push the frame 22 away from the 35 comb and the lock knife blade 21 away from the tips 20 so that the vibrator gears may be raised or lowered under influence of the pattern mechanism. This action takes place while the blank portions of the cylinders are 40 passing the vibrator gears 13. The cam is so timed that the lock knife is drawn inwardly by the spring to have holding engagement with the tips 20 just prior to engagement of the toothed portions of the cylinders with 45 the vibrator gears. By changing the position of screw 36 the range of movement of the lock knife may be varied and by changing the position of screw 35 the position of the lever 29 may be altered within limits.

50 From the foregoing it will be seen that I have provided a simple connection between the lock knife operating cam 28 and the blade 21 which consists essentially of two parts one of which is actuated by the cam 55 and carries an abutting surface or element 36 which has engagement with a portion of the lock knife frame. The force tending to move the lock knife against the action of the spring is so transmitted as to place the coacting parts 60 in compression and the objectionable twist present in constructions heretofore used where set screws have been employed is effectively eliminated. It will also be seen that the parts are so arranged that the spring 37 holds the actuating lever against a fixed stop

and the lock knife frame against the abutting surface when the cam is in such position as not to move these parts.

Having thus described my invention it will be seen that changes and modifications may 70 be made therein by those skilled in the art without departing from the spirit and scope of the invention and I do not wish to be limited to the details herein disclosed, but what I claim is:

1. In a loom having upper and lower rotating actuator cylinder gears, vibrator levers movable to be operatively related to one or the other of said gears at a time, a lock knife to engage the vibrator levers and limit movement of the latter, a cam rotating with the upper cylinder gear, a lever engaging and rocked by the cam, a frame for the lock knife pivotally mounted on the loom and having direct engagement with a 80 part of the lever, and separate spaced pivotal supports for the frame and lever which is rocked by the cam.

2. In a loom having upper and lower rotating actuator cylinder gears, vibrator levers movable to be operatively related to one or the other of said gears at a time, a lock knife to engage the vibrator levers and limit movement of the latter, a cam rotating with one of the cylinders, an actuating lever engaging and movable by the cam, an abutting element carried by the lever, and a pivotally mounted frame for the lock knife engaging the abutting surface to move the knife away from the vibrator levers.

3. In a loom having upper and lower rotating actuator cylinder gears, vibrator levers movable to be operatively related to one or the other of said gears at a time, a lock knife to engage the vibrator levers and limit movement of the latter, a cam rotating with one of the cylinders, two pivoted members, one engaging the cam and the other supporting the lock knife, said members having direct engagement with each other, and spaced pivotal supports for the members, one pivotal support adjacent each actuator cylinder.

4. In a loom having upper and lower rotating actuator cylinder gears, vibrator levers movable to be operatively related to one or the other of said gears at a time, a lock knife to engage the vibrator levers and limit movement of the latter, a cam rotating with one of the cylinders, two pivoted members, one engaging the cam and the other supporting the lock knife; and transmitting the force of the cam to the lock knife by placing the contacting parts of the members under compression strain, and spaced pivotal supports for the members, one pivotal support adjacent each actuator cylinder.

5. In a loom having upper and lower rotating actuator cylinder gears, vibrator levers movable to be operatively related to one

or the other of said gears at a time, a lock knife to engage the vibrator levers and limit movement of the latter, a cam rotating with one of the cylinders, two pivoted members, one engaging the cam and the other supporting the lock knife, and an adjusting element carried by one member and engaging the other and having its axis substantially parallel to the direction of transfer of force 5 from the cam engaging member to the lock knife member.

6. In a loom having a pair of oppositely rotating actuating cylinder gears, a set of vibrator levers located between the gears and movable each to operative relation with respect to either gear, a fixed device, a lock knife member to engage the vibrator levers, resilient means to hold the knife in vibrator lever engaging position, a cam rotating with 10 one cylinder gear, an actuating lever movable by the cam, and means establishing contact between the lock knife member and the actuating lever, the resilient means holding the actuating lever against the fixed device 15 and maintaining the means in contacting relation.

7. In a loom having a pair of oppositely rotating actuating cylinder gears, a set of vibrator levers located between the gears and movable each to operative relation with respect to either gear, a fixed device, a lock knife member to engage the vibrator levers, a resilient element, an actuator lever and a cam to move the latter, the resilient element 20 holding the lever and lock knife member in contact and also holding the lever against the fixed device.

8. In a loom having upper and lower rotating actuator cylinder gears, vibrator levers movable to be operatively related to one or the other of said gears at a time, a lock knife to engage the vibrator levers and limit movement of the latter, a cam rotating with one of the cylinders, two pivoted members, one engaging the cam and the other supporting the lock knife, a resilient element, and a fixed stop, the resilient element holding the members normally in contacting operative relation, and also holding one of said members 25 against the fixed stop.

9. In a loom having upper and lower rotating actuator cylinder gears, vibrator levers movable to be operatively related to one or the other of said gears at a time, a lock knife to engage the vibrator levers and limit movement of the latter, a cam rotating with one of the cylinders, two pivoted members, one engaging the cam and the other supporting the lock knife, a resilient element, an a fixed stop, the resilient element holding the members normally in contacting operative relation, and also holding the cam engaging member against the fixed stop.

10. In a loom having upper and lower ac- 30 tuator cylinders and a set of vibrator levers

between the cylinders, a cam rotating with one of the cylinders, a fixed structure, a lock knife for the levers, a lever to engage the cam, an adjustable stop on the lever to engage the fixed structure and limit movement 35 of the lever toward the cam, and an adjustable connection between the lever and the lock knife, movement of the lever communicating force through the connection to the lock knife, the stop and connection being 40 each movable independently of the other.

In testimony whereof I have hereunto affixed my signature.
